UNITED STATES PATENT OFFICE.

ALONZO E. RHOADES, OF HOPEDALE, MASSACHUSETTS, ASSIGNOR TO DRAPER COMPANY, OF HOPEDALE, MASSACHUSETTS, A CORPORATION OF MAINE.

WARP STOP-MOTION FOR LOOMS.

1,082,045.

Specification of Letters Patent. Patented Dec. 23, 1913.

Application filed April 29, 1911. Serial No. 624,120.

To all whom it may concern:

Be it known that I, ALONZO E. RHOADES, of Hopedale, in the county of Worcester, in the State of Massachusetts, have invented 5 certain new and useful Improvements in Warp Stop-Motions for Looms, of which the following is a specification.

The primary object of the present invention is to relieve the warp threads of the weight of 10 the warp stop detectors of a warp stop motion to a substantial extent so as to minimize the drag of the warp threads upon the detectors. In the case of fragile and slack sized warp threads, the friction caused by the warp stop 15 detectors results in warp breakage, thus involving unnecessary stoppage of the loom. Accordingly, the aim of the present invention is to reduce this friction.

In carrying out this main object, the warp 20 stop detectors are made of small size so as to reduce their weight, and they are also arranged in two banks so as to coöperate with the two planes of the warp threads made by the lease rods. The supports for 25 the warp stop detectors and for the lease rods are arranged so as to facilitate their removal from the loom when a fresh warp is to be drawn in and applied to the loom.

The present improvements are illustrated 30 in the accompanying drawings, wherein—

Figure 1, is a side view of the warp stop motion and co-acting devices, enough only of the loom being shown to enable the improvements to be understood. Fig. 2, is a 35 plan view of the warp stop motion and the co-acting parts of the loom. Fig. 3, is a transverse vertical section in the plane indicated by the line 3—3 in Fig. 2. Fig. 4, is a rear view of a portion of the mechanism, 40 the support for one end of the lease rods being shown in section. Fig. 5, is a detail view of one of the detectors. Fig. 6, is a detail section in the plane indicated by the line 45 6—6 in Fig. 3, and illustrating the removable mounting of one end of the supporting rods for the warp stop detectors.

In Fig. 1, a portion of the loom frame is shown in dotted lines. A, is the cam shaft 50 carrying a cam a, which vibrates the feelers B, B, which feel for a warp stop detector when occupying an abnormal position due to the breaking or undue slackening of its warp thread. The intervening connections between the cam and the feelers will be ex-

plained after the other characteristics have 55 been described. The drawings illustrate the warp threads which feed forwardly in the direction indicated by the arrow b, as the cloth is woven. The warp threads are divided into two intersecting planes or sections 60 by lease rods C. The warp stop detectors D, are arranged in two banks which coöperate with the lower planes of the intersecting warp threads as shown in Fig. 3, being in this respect similar to the arrangement 65 shown in reissued Letters Patent of Coldwell and Gildard, No. 11,923, July 30, 1901.

The detectors are made of flat thin sheet metal approximately .008 of an inch in thickness. Each detector (Fig. 5) has a 70 thread eye c, through which one warp thread passes and a pivot hole d, through which loosely passes a supporting rod E. There are two of the supporting rods E, one for 75 each bank of detectors. Each detector is thus supported at bottom and top by its rod E, and by its warp thread. The arrangement is such that when the warp threads are intact the detectors stand at an angle so that the weight of each is borne partly by the 80 warp thread, but preponderatingly by the supporting rod. The detectors are made as short as is consistent with the performance of their offices, so that only a minimum weight is thread-supported. Each detector 85 extends above its thread eye c, only far enough to have the requisite strength and not far enough to come in contact with the overlying warp threads. Consequently, each thread comes in contact only with its own 90 detector and is not subjected to any chafing action by reason of the other detectors either in its own bank or in the other bank. No part of one detector can ever come in contact with a thread in the crossing warp-plane, 95 that is to say, with any threads passing through the bank of detectors to which it does not belong. Hence, the friction on the warp thread due to the presence of the detectors is reduced to a minimum and hence 100 the warp stop motion is adapted to be used with the finest, most fragile and least sized yarns. The detectors, by reason of their loose pivoting on the supporting rods E, are free to slide transversely of the loom 105 (lengthwise of the supporting rods) thereby facilitating access to a fallen detector to rethread it, and to enable the organization

to be used with varying numbers of warp threads.

By reason of the lightness of the detectors and their arrangement in two banks co-
5 operating with the lower planes of the leased threads the warp stop motion can be used with warps having a large number of threads per inch.

In case a thread breaks its detector drops
10 into a position to obstruct the movement of the corresponding feeler B, as shown at the right in Fig. 3. Consequently, the detectors normally stand in an inclined position with their weights partly resting on the warp threads. In order to maintain the detectors in this normal inclined position two positioning bars F, are employed, one for each bank of detectors. Each positioning bar F, is located in advance of its bank of de-
15 tectors so that the feeding strain on the warp threads causes the detectors to abut against it, as shown in Fig. 3. The positioning bars thus prevent the detectors from assuming a vertical position due to the ad-
20 vance of the warp threads, and maintain the two banks of inclined detectors in parallelism.

In case a warp thread breaks, its detector drops upon a fixed stop bar G, as shown at
30 the right in Fig. 3. There are two of these stop bars G, one for each bank of detectors. These stop bars are preferably notched at their upper edges, as likewise are the lower edges of the feelers B, as illustrated and as
35 common in the art, so as to avoid twisting the flat detectors under the feeling strain. When one of the detectors drops it occupies an inclined position approximating the horizontal and lies at an angle to a vertical plane
40 through its pivot bar and it is then in the path of the corresponding feeler B. Consequently, the full movement of the feeler is obstructed and as the result the loom is stopped in a well-known way. In drop-
45 ping from its normal position to its loom stopping position, each detector is required to swing through rather less than ninety degrees of arc, so that it promptly gets to stopping position. All parts of a dropped
50 detector are wholly out of the path of any of the warp threads.

The shafts H, of the feelers B, the supporting rods E, and the positioning bars F, are supported on a stationary frame I, se-
55 cured to fixed brackets J, fastened to the two side frames of the loom.

Each of the lease rods C, is supported at each end by one end of a rocking lever K, pivotally mounted at its middle on a stud
60 e, on the frame I, so that the lease rods may yield under the sway of the warp threads. A fixed central bar L, supported by the frame I, extends beneath the warp threads at the crossing of their leased planes, as
65 shown in Fig. 3, so as to reduce any tend-

ency of the warp threads to sag under the weight of the detectors.

The supporting rods E, with the detectors D, strung thereon, are conveniently removed to facilitate drawing in and the placing of a fresh warp. Each supporting rod E, at each end rests in an open slot f, shown in Fig. 6, in a portion of the frame I, and is held in place therein by a removable pin g. By withdrawing the pin g, the supporting rod with the detectors strung thereon can be removed. These slots f, are rearwardly inclined, as shown in Fig. 3, so that there is no danger of the rods being displaced by the drag of the warp threads during weaving even if the pin g, should be omitted. The lease rods are likewise easily removable. The end of each lease rod rests in a hole in one end of one of the levers K, and is prevented from endwise displacement by an external swinging gate M, pivoted at h, to the lever K. When it is desired to remove a lease rod one of the corresponding gates M, is swung upwardly out of the way and the lease rod can then be removed by sliding it endwise. It is only necessary to slide a lease rod far enough to release it from the hole in the opposite lever K, and then, when out of register therewith, it can be slid in the opposite direction far enough to free its unlocked other end. A leather bushing i, is shown between the end of each lease rod and the hole in the lever K, in which it fits.

The feeler shafts H, H are vibrated in unison from the cam a. That cam acts upon a toe or follower, N, pivoted at j, to a bunter-carrier K', which co-operates with the loom stopping mechanism in a manner well known in the art, a similar bunter-carrier, for example, being shown at A, in United States Letters Patent of Clement No. 645,912, March 20, 1900. The toe N, is connected by a link O, with an arm P, which is loosely hung on a rock-shaft Q. The toe N, is held against the cam a by a spring which is not shown since the arrangement is similar to that shown in the United States Letters Patent of Draper No. 797,671 August 22 1905. This arm P is yieldingly connected with the rock shaft Q, by means of a spring Z, (Fig. 2), and it has a projecting stud m, which, on the upstroke of the link O, encounters a projecting stud n, of a collar o, which is fast on said shaft Q, as in United States Letters Patent of Ambler, No. 885,130, April 21, 1908. The downpull of the link O, acts through the spring Z, to rock the shaft Q. Shaft Q, has a crank arm p, connected by a link R, with a crank arm S, on the front feeler shaft H. At one extreme end said front feeler shaft H, has a crank arm T (Fig. 1) connected to a similar arm U, on the rear feeler shaft H, by a link V. Accordingly, the two feelers vibrate in unison. 133

In case a feeler on its down stroke encounters a fallen detector, the spring Z, can yield thereby avoiding damage.

The mechanism between the bunter-carrier K' and the loom stopping mechanism is not shown because constituting no part of the present invention. Such intervening mechanism can be employed as is shown in the aforesaid patent of Clement, No. 645,912. During the normal running of the loom, the cam a acts upon the follower N, thereby vibrating it in one direction, and a spring (not shown, but similar to that described in the Draper Patent No. 797,671) moves the follower in the opposite direction. This vibration of the follower is communicated through the illustrated intervening mechanism to the feelers B. In case, however, a detector drops and prevents the vibration of the feelers, the follower N can no longer be swung on its axis j by the cam a. On the contrary, the cam a when it then encounters the follower N, does not vibrate the follower, but acts through the follower to lift the bunter-carrier K', the connecting rod O then swinging about its upper pivot. This lifting of the bunter-carrier K' swings a lever such as is shown in said Clement Patent, No. 645,912, and unships the usual shipper lever of the loom, thereby stopping the loom in a well-known manner. Substantially no strain is brought upon the fallen obstructing detector.

The link V, connects the ends of the two feeler shafts H, H, outside of the frame I, and has an upwardly projecting easily accessible handle W, by means of which both feelers can be simultaneously retracted thereby enabling fallen detectors to be conveniently handled.

I claim:—

1. A warp stop motion for a loom having, in combination, a plurality of supporting rods extending transversely of the loom beneath the warp; a bank of thin sheet metal detectors loosely pivoted at their lower ends on each of said rods and transversely movable thereon and each detector having a thread-eye at its upper end through which one of the warp threads passes; and a positioning bar forward of each bank of detectors which maintains said detectors in an inclined position when the warp threads are intact, the forward feed of the warp threads bringing the detectors against said positioning bar, and the several positioning bars maintaining the several banks of inclined detectors in parallelism.

2. A warp stop motion for a loom having, in combination, a supporting rod extending transversely of the loom beneath the warp; a bank of thin sheet metal detectors loosely pivoted at their lower ends on said rod and transversely movable therein, and each having a thread-eye at its up-

per end through which one of the warp threads passes; and a positioning bar forward of said bank of detectors which maintains said detectors in an inclined position when the warp threads are intact, the forward feed of the warp threads bringing the detectors against said positioning bar. 70

3. A warp motion for a loom having, in combination, a supporting rod extending transversely of the loom beneath the warp; a bank of thin sheet metal detectors pivoted at their lower ends on said rod and each having a thread-eye at its upper end through which one of the warp threads passes; and a positioning bar forward of said bank of detectors which maintains said detectors in an inclined position when the warp threads are intact, the forward feed of the warp threads bringing the detectors against said positioning bar. 75 80 85

4. A warp stop motion for looms comprising lease rods dividing the warp threads into two intersecting planes; two supporting rods extending transversely of the loom beneath the warp threads and at opposite sides of the intersection of said leased planes; and two parallel banks of thin sheet metal detectors supported respectively by the lower crossing planes of the warp threads between the lease rods and likewise by said rods, each detector being pivoted to one of said rods and having an eye at its upper end through which one of the warp threads passes, no part of one detector ever encountering a thread in the crossing warp-plane. 90 95 100

5. A warp stop motion for looms comprising lease rods dividing the warp threads into two intersecting planes; two supporting rods extending transversely of the loom beneath the warp threads and at opposite sides of the intersection of said leased planes; and two parallel banks of thin sheet metal detectors supported respectively by the lower crossing planes of the warp threads between the lease rods and likewise by said rods, each detector being pivoted to one of said rods and having an eye at its upper end through which one of the warp threads passes. 105 110 115

6. A warp stop motion for looms having, in combination, a supporting rod extending cross-wise of the loom beneath the warp threads; a bank of thin sheet metal detectors, each of which is pivoted at its lower end to said supporting rod and having an eye at its upper end through which one of the warp threads passes; a stationary stop bar back of said supporting rod which supports the free end of a fallen detector, so that said fallen detector lies at an angle to a vertical plane; and a rising and falling vibrating feeler which encounters said fallen detector upon its downward movement. 120 125

7. A warp stop motion for looms having, in combination, a supporting rod extend- 130

ing cross-wise of the loom beneath the warp threads; a bank of thin sheet metal detectors, each of which is pivoted at its lower end to said supporting rod and having an eye at its upper end through which one of the warp threads passes; a stationary stop bar back of said supporting rod which supports the free end of a fallen detector; and a rising and falling vibrating feeler which 10 encounters said fallen detector upon its downward movement.

8. A warp stop motion for looms having, in combination, a bank of thin sheet metal detectors, each of which is pivoted at its lower end and is normally upheld by a warp thread; a stationary stop bar which supports a fallen detector, so that it lies at an angle to the vertical; and a rising and falling vibrating feeler which encounters 20 said fallen detector upon its downward movement.

9. A warp stop motion for a loom having, in combination, lease rods dividing the warp threads into two intersecting planes; two removable supporting rods extending transversely of the loom beneath the warp and at opposite sides of the intersection of said leased planes; two banks of thin sheet metal detectors loosely pivoted at their lower ends 25 on said respective rods and transversely movable thereon, and each having a thread-eye at its upper end through which one of the warp threads passes, the two banks of detectors being supported respectively at 30 their upper ends by the lower crossing planes of the warp threads; a permanent positioning bar forward of each bank of detectors which maintains said detectors in an inclined position when the warp threads are 35 intact, the forward feed of the warp threads bringing the detectors against said positioning bar, and the two positioning bars maintaining the two banks of inclined detectors in parallelism; a stationary stop bar back 40 of each of said supporting rods which supports the free end of a fallen detector so that said fallen detector lies at an angle to a vertical plane; and a rising and falling vibrating feeler for each bank of detectors 45 which upon its down stroke encounters a fallen detector.

10. A warp stop motion for a loom having, in combination, a plurality of removable supporting rods extending transversely of the loom beneath the warp; a plurality 55 of banks of thin sheet metal detectors loosely pivoted at their lower ends on said respective rods and transversely movable thereon, and each having a thread-eye at its upper end through which one of the warp threads 60 passes; a permanent positioning bar forward of each bank of detectors which maintains said detectors in an inclined position when the warp threads are intact, the forward feed of the warp threads bringing the 65 detectors against said positioning bar, and the several positioning bars maintaining the several banks of inclined detectors in parallelism; a stationary stop bar back of each 70 of said supporting rods which supports the free end of a fallen detector so that said fallen detector lies at an angle to a vertical plane; and a rising and falling vibrating feeler for each bank of detectors which upon its down stroke encounters a fallen detector. 75

11. A warp stop motion for a loom having, in combination a removable supporting rod extending transversely of the loom beneath the warp; thin sheet metal detectors loosely pivoted at their lower ends on said 80 rod and transversely movable thereon, and each having a thread-eye at its upper end through which one of the warp threads passes; a permanent positioning bar forward of the detectors which maintains said 85 detectors in an inclined position when the warp threads are intact, the forward feed of the warp threads bringing the detectors against said positioning bar; a stationary stop bar back of said supporting rod which 90 supports the free end of a fallen detector so that said fallen detector lies at an angle to a vertical plane; and a rising and falling vibrating feeler which upon its down stroke 95 encounters a fallen detector.

In witness whereof, I have hereunto signed my name in the presence of two subscribing witnesses.
